STEAM CONDENSER.

Application filed August 14, 1925. Serial No. 50,181.

This invention relates to surface condensers, but more particularly to that type of surface condenser comprising surface cooling tubes extending longitudinally through a chamber across the path of the steam flow. It is an object of this invention to distribute the steam longitudinally along the length of the condenser in quantities proportionate to the steam condensing capacity of the various vertical sections. In condensers in which the cooling tubes extend longitudinal of the condenser, vertical sections along the length of the tubes vary in their steam condensing capacity since the cooling water is supplied to the tubes at one end of the condenser and discharged at the other end resulting in unequal temperatures along the length of the tubes since the water raises in temperature upon absorbing heat from the steam progressively from the inlet to the discharge ends. The cooler end consequently has greater steam condensing capacity and the warmer end less steam condensing capacity, the vertical sections therebetween having decreasing steam condensing capacity as they approach the warm end. Unless special provision is made as for instance disclosed in application Serial No. 743,695 of Paul A. Bancel, filed October 15, 1924, steam will not penetrate the banks of tubes at the cool end as deeply as at the warm end, being more quickly condensed upon coming in contact with the tubes. By this invention it is proposed to divide the condenser vertically into a plurality of compartments substantially sealed from each other at the bottom of the condenser and at least part way to the upper bank of tubes to prevent steam from passing between compartments longitudinally along the tubes. In the various sections different degrees of vacuum are maintained at the bottom of the condenser so as to draw steam to equal depths of penetration. This is accomplished by throttling the air outlets and it is accordingly a further object of this invention to conveniently throttle the exit for air and uncondensable gases so that if desired, a single vacuum pump may be employed to maintain suitable vacuums in the various vertical sections of the condenser to produce equal depth of steam penetration along the length of the condenser.

The invention will be more clearly under-

stood by reference to the drawings forming part of the specification and in which similar reference characters refer to similar parts.

Figure 1 is an end view partly in section of a condenser, portions being broken away,

Figure 2 is a side view with portions broken away of a part of a condenser with the devaporizer removed,

Figure 3 is a front view of a throttle plate at the outlet for air and uncondensable gases, and

Figure 4 is a cross sectional view of the throttle plate along the line 4-4 of Figure 3 looking in the direction of the arrows.

In the drawing, A represents the casing 70 of a condenser having a steam inlet at B, an outlet C for condensate, and an outlet D for air and uncondensable gases leading to a devaporizer E of approved design. Within the casing A, a plurality of steam 75 condensing tubes F are arranged transverse to the path of the steam entering at the inlet B. Cooling water is adapted to pass through the tubes F from an inlet (not shown) and to be discharged into a head G. 80

In operation, the temperature of the tubes F increases along the length of the tubes in the direction of the discharge head G which creates a condition of greater steam condensing capacity at the cooler ends of 85 the tubes than at the warmer end. The condenser thus constructed may be said to have varying steam condensing capacity in vertical transverse sections along the length of the tubes. As a result of this condition, the 90 tendency of steam entering at the inlet B is to penetrate more deeply in warmer sections nearer the discharge head G than at the cooler sections more remote therefrom since more steam is condensed per unit of 95 area of tube surface at the cooler portions of the tubes than at the warmer surfaces.

In order to counteract the tendency of steam to penetrate less deeply in the cooler sections, means is provided to divide the interior of the shell A into compartments in which the degree of vacuum varies correspondingly with the varying specific steam condensing capacity by which is meant the capacity per unit of tube area. It will be seen that if a greater vacuum is maintained in the cooler compartments than in the warmer compartments, the tendency of the

steam is to penetrate in the cooler sections condenser. The wall T is provided with a more deeply than would normally be the case if the same degree of vacuum were maintained in all of the compartments. The ideal condition sought is to maintain such a degree of vacuum within each compartment so that the steam entering at the inlet B will penetrate to an equal depth between the tubes F throughout the length of the condenser.

To this end the condenser is divided into compartments by means of partitions H which may be the usual tube support sheets sealed at the bottom and at the sides near the bottom in suitable grooves J to prevent leakage of steam from one compartment to another. The condenser is provided with two devaporizers E arranged for attachment to suitable flanges K cast integrally with the shell A. In the embodiment illustrated there are three partitions H provided to divide the interior of the casing A into four compartments, that at the end nearest the discharge head G having the least specific steam condensing capacity and the other three compartments being of progressively increasing capacity toward the colder end of the condenser.

The fingers K and the supporting ribs L form a chamber O for accommodating water supplied to the devaporizer E and an air and vapor inlet P. The lower opening Q formed by the flanges K is adapted to form an inlet from the chamber P to the devaporizer E for the accommodation of air and uncondensable gases and an outlet from the devaporizer E to permit condensate to flow back through a trap R and through the air inlet D into the bottom of the condenser shell A and thence to the condensate outlet C. A suitable vacuum is produced by a vacuum pump (not shown) attached to the air outlet S of the devaporizer E.

Each devaporizer E is arranged to serve two compartments formed by the partitions H and to this end one of the partitions H extends through the air outlet D to a wall T interposed between the devaporizer E and the air outlet D. The wall T extends downwardly into the trap R to prevent air from passing under the wall directly to the devaporizer. The wall T is provided with throttle plates shown in detail in Figures 3 and 4 which are adapted to restrict the flow or escape of air from the compartments within the condenser to the devaporizer E. The amount of restriction of air provided by the throttle plates is determined by the difference of the degree of vacuum desired in the various compartments. The warmer compartments will therefore be provided with greater restriction to the flow of air since a somewhat greater vacuum is required in the cooler compartments to draw more steam toward the cooler portions of the

plurality of apertures U into which plates V are inserted and held by means of the clamp W and bolt X. In each plate V, a number of holes Y of suitable diameter are provided sufficient in size and number to restrict the flow of air to the devaporizers E to the proper degree which may be determined by experiment. The plates V may be flanged as at Z and form a seal with the wall T, a suitable gasket being provided. The plates V may be inserted in the apertures U by removing the trap R whereupon they are readily accessible from the outside.

Thus by the above construction are accomplished among others the object hereinbefore referred to.

I claim:

1. A surface condenser having an inlet for vapor to be condensed and an outlet for air and non-condensable gases comprising steam condensing tubes having varying specific steam condensing capacity in vertical sections along their length, means for dividing the condenser vertically into compartments of different specific steam condensing capacities, and means at said air outlet to throttle the passage of air therefrom and to maintain in said compartments degrees of vacuum proportionate to the steam condensing capacity thereof.

2. A surface condenser having a steam inlet and an outlet for air and non-condensable gases comprising steam condensing tubes having varying specific steam condensing capacity in vertical sections along their length, means for dividing the condenser vertically into compartments of different steam condensing capacities, a wall at said air outlet, and throttle plates in said wall through which the air and non-condensable gases from the compartments are adapted to be drawn whereby different degrees of vacuum are maintained in said compartments corresponding to their steam condensing capacity.

3. A surface condenser having a steam inlet and an outlet for air and non-condensable gases comprising steam condensing tubes having varying specific steam condensing capacity in vertical sections along their length, means for dividing the condenser vertically into compartments of different steam condensing capacities, a wall at said air outlet, and removable throttle plates in said wall through which the air and non-condensable gases from the compartments are adapted to be drawn whereby different degrees of vacuum are maintained in said compartments corresponding to their steam condensing capacity.

4. A surface condenser having a steam inlet and an outlet for air and non-condensable gases including steam condensing tubes extending transverse to the path of steam

- flow and having different steam condensing capacities along their length, a devaporizer attached to the condenser at the air outlet, means for dividing the condenser vertically into compartments having varying specific steam condensing capacity, a wall interposed between said air outlet and said devaporizer, and perforated plates in said wall to throttle the escape of air to the devaporizer from said compartments, whereby a degree of vacuum may be maintained in each compartment sufficient to draw the steam to the lowermost bank of tubes therein.
- 5 10 15 20 25 30 35 40 45 50
6. A surface condenser having a steam inlet, an outlet for condensate and an outlet for air and non-condensable gases, a plurality of steam condensing tubes arranged transverse to the path of steam flow and having varying specific steam condensing capacity in vertical sections along their length, a devaporizer at the air outlet, partitions dividing the condenser into at least two compartments having different specific steam condensing capacity, said partitions dividing said air outlet, a wall at said outlet, and perforated plates in said wall to throttle the escape of air to said devaporizer, whereby different degrees of vacuum may be maintained in said compartments corresponding to their steam condensing capacity.
- In testimony whereof I have signed this specification.
- JOHN F. KIRGAN.
